UNITED STATES PATENT OFFICE.

ELIJAH MCCOY, OF DETROIT, MICHIGAN, ASSIGNOR TO JOHN TRIX, OF SAME PLACE.

LUBRICATOR.

SPECIFICATION forming part of Letters Patent No. 663,976, dated December 18, 1900.

Application filed May 5, 1900. Serial No. 15,579. (No model.)

To all whom it may concern:

Be it known that I, ELIJAH MCCOY, a citizen of the United States of America, residing at Detroit, in the county of Wayne and State of Michigan, have invented certain new and useful Improvements in Lubricators, of which the following is a specification, reference being had therein to the accompanying drawings.

This invention relates to that kind of lubricators known as "displacement-lubricators," and it has particular reference to the novel construction and arrangement of a sight-feed fitting and of a water seal at the discharge end of the condenser, all as more fully hereinafter described, and shown in the accompanying drawings, in which—

Figure 1 is an elevation of my improved lubricator as connected up to the steam-supply pipe of an engine. Fig. 2 is a vertical central section through the lubricator detached, and Fig. 3 is a detached vertical section showing the construction of the water seal.

In the drawings, A is the lubricator-cup, and B is the gage-glass connected thereto and provided with a screw-plug C for filling the cup with the lubricant and with a drainage-cock D, all in the usual manner.

E is a hollow fitting forming a sight-feed chamber a by means of glass disks secured opposite each other in the front and rear walls of the chamber in the known manner. This fitting is mounted on top of the oil-cup by means of a hollow arm b on the fitting, which screws into an orifice in the top of the oil-cup. Another hollow arm c, provided on top of the fitting, forms the means for connecting it with a suitable condenser head or pipe d, which communicates with the source of steam under control of a valve e, and a third hollow arm f, projecting laterally, forms the means for connecting it to the steam-pipe of the engine. The hollow arms c b are connected by a condensed-water passage formed in the body of the fitting to one side of the sight-feed chamber with a suitable valve h, arranged to control this passage. In the lower end of this passage is secured the tube i, which forms a continuation of this passage down to near the bottom of the cup. The lower end of this tube is provided with a water seal essentially consisting of a well or cup j, surrounding the discharge-opening of the tube, and a deflector k, secured slightly above

the cup to leave an opening l between the deflector and the cup. The cup and deflector 55 may be directly supported on the tube, as shown in Fig. 3, suitable openings m being made for the discharge of the condensed water from the tube in the cup, and the under side of the deflector is preferably formed concave. A pin-hole n may be provided in the bottom of the cup to permit a slow drainage to prevent freezing.

The sight-feed chamber has an oil-discharge port o in the top thereof which communicates through a short and relatively wide passage p with the hollow discharge-arm f, which conducts the oil into the steam-pipe F through a short valved connection G. A nozzle q, projecting into the sight-feed chamber through 70 the bottom, forms, as usual, the oil-inlet into the sight-feed chamber. This nozzle is secured in position by means of a tube r, which is screwed at the lower end into the nipple of the stuffing-box s and seated at its upper 75 end in the tubular extension q' of the nozzle. A valve-stem t passes upwardly through the stuffing-box s and tube r and has a screw-threaded engagement in the extension q', which is provided with a valve-seat q² and admission-ports v.

The parts being constructed as shown and described it will be seen that the hydrostatic column for the displacement of the oil is formed in the pipe d, passage g, and extension i, while the sight-feed chamber a is filled with water of condensation by communicating with the steam-pipe through the arm f, and in the normal operation the oil in the cup will therefore be displaced and flow through 80 the ports v, nozzle q, sight-feed chamber a, port o, passage p, and arm f into the steam-pipe and to the part to be lubricated, as in the usual operation of sight-feed lubricators of like character.

My construction has several important advantages. One is in the construction of the water seal at the discharge end of the tube i. Heretofore a water seal has been provided by turning up the end of the pipe or inserting it 90 into an open well or cup; but I have found that in opening the cup to the atmosphere to drain off the water from the cup in refilling it with the lubricant the water is blown out of such well or cup if the valve h should not 105 be closed tightly or, what happens more fre-

quently, has a leaky seat. This blowing out of the water under such circumstances is prevented in my construction by the deflector over the cup, and thus I preserve the water seal under all contingencies and guard against all possibility of wasting oil (by displacement through the water-column) or of bringing the steam into direct contact with the oil in the cup.

10 Incidentally it may be mentioned here that it is impractical to use a check-valve at the end of the tube *i*, as this gives the oil no room for possible expansion when the valves *h* and *t* are closed.

15 A further advantage of my construction is that the lubricator when put into operation will begin to feed quickly, as it requires but a small hydrostatic pressure to displace the oil owing to the absence of the internal friction—that is, the oil feeds directly from the top of the cup into the nozzle and sight-feed chamber, and thence is fed by its own gravity through a large opening in the discharge-arm into the steam-pipe.

20 25 It will be observed that the arm *b* of the fitting in reality forms the neck of the cup, and the oil thus flows directly from this neck into the nozzle. Further, there is only a relatively small quantity of oil in the annular chamber in the neck, and the walls of this annular chamber are in near heat-conducting proximity to the live steam in the arm *f*, and the small quantity of oil in the neck is thus readily heated and feeds freely, and certain 30 35 oils which are difficult to feed with other lubricators can be used in my cup. There is also no possibility of the oil-passages becoming clogged up.

30 The advantages which the construction offers on account of its simplicity, from the manufacturer's point of view, are also considerable and will be well understood by those skilled in the art.

What I claim as my invention is—

40 45 1. In a condensation-displacement lubricator, the combination with the oil-reservoir, of an inlet-tube for the water of condensation leading through the top of said reservoir to near the bottom thereof and having its lower end closed, a cylindrical cup closed at the bottom and open on top secured to the lower end of said tube and adapted to form a water seal around the discharge end of said inlet-tube, perforations in the side of said tube 50 55 near the bottom of the cup, and a deflector secured upon the inlet-tube above the cup and forming an annular discharge-outlet between it and the top of the cup.

60 65 2. In a condensation-displacement lubricator, the combination of the oil-reservoir *A*, a fitting *E* having an upwardly-extending arm *c*, to which the condenser is attached, and a downwardly-extending arm *b* secured in the top of the reservoir and connected by a passage through the fitting with the arm *c*, a valve *h* controlling the flow of the water of condensation through said passage, the tube

i secured in the lower end of said passage and extending down to near the bottom of the oil-reservoir, the cup *j* secured to the lower end of said tube and forming a water seal for said tube, and the deflector *k* vertically adjustably secured upon said tube above the cup and independently thereof.

70 75 3. In a condensation-displacement lubricator, the combination of the oil-reservoir, a fitting having a downwardly-extending arm connecting it to the top of the reservoir and an upwardly-extending arm connecting it to the condenser, a valve-controlled passage connecting the two arms through the body of the fitting and forming an inlet for the water of condensation into the reservoir, a sight-chamber formed in the body of the fitting, a lateral discharge-arm from said fitting communicating with the top of the sight-chamber, and a valve-controlled nozzle in the lower arm of the fitting leading into the bottom of the sight-chamber, said lower arm of the fitting being chambered and forming an upper 80 85 extension of the reservoir in direct communication with the nozzle and in heating proximity of the discharge-arm.

90 95 4. In a condensation-displacement lubricator, the combination of the oil-reservoir *A*, formed with an orifice in its top, the fitting *E* having an inlet-arm *b* secured in said orifice and forming the neck of the oil-reservoir, a valve-controlled passage *g* through said fitting, a condenser-pipe *d* communicating with the upper end of said passage, an inlet-tube *i* extending from the lower end of said passage into the oil-reservoir, a sight-feed chamber *a* in the body of the fitting, the lateral discharge-arm *f* and the nozzle *g* in the inlet-arm through which the neck of the oil-reservoir is in direct communication with the sight-chamber, the tubular extension *q* of the nozzle, the tube *r* securing said nozzle in position and the valve-stem extending through 100 105 110 said tube.

115 120 5. The combination of an oil-reservoir, a sight-feed fitting having a downwardly-extending arm, connecting the fitting into the top of the oil-reservoir, a sight-chamber centrally in the body of the fitting, and in direct communication with the oil-reservoir through a passage in the aforesaid arm, an upwardly-extending arm on said fitting communicating through a passage in the fitting with the downwardly-extending arm; a condenser-pipe connecting said upwardly-extending arm with the steam-pipe, and a laterally-extending arm on said fitting connecting it with the steam-pipe and forming a steam-chamber contiguous to the sight-chamber and connected by a passage in the fitting with said sight-chamber for the discharge of the oil into said chamber.

125 In testimony whereof I affix my signature in presence of two witnesses.

ELIJAH MCCOY.
